Specification for Design.

Patented Oct. 4, 1921.

Application filed June 6, 1921. Serial No. 475,442. Term of patent 14 years.

To all whom it may concern:

Be it known that I, RUSSELL D. BELDEN, a citizen of the United States, residing at Buffalo, in the county of Erie and State of New York, have invented a new, original, and ornamental Design for Tire-Casings, of which the following is a specification, reference being had to the accompanying drawings, forming part thereof.

In the drawings,—

Figure 1 is a plan view of a section of the tread of a tire embodying the features of the present invention.

Fig. 2 is a transverse section therethrough.

I claim:—

The ornamental design for a tire casing, as shown.

RUSSELL D. BELDEN.
